UNITED STATES PATENT OFFICE.

JOHN SKLAR, OF BROOKLYN, NEW YORK.

OBSTETRICAL FORCEPS.

1,033,627.

Specification of Letters Patent.

Patented July 23, 1912.

Application filed February 15, 1912. Serial No. 677,667.

To all whom it may concern:

Be it known that I, JOHN SKLAR, a citizen of the United States, residing at Brooklyn, county of Kings, State of New York, 5 have invented new and useful Improvements in Obstetrical Forceps, of which the following is a specification.

This invention relates to obstetrical forceps, and the main feature of the invention 10 is to provide the instrument with an indicator whereby the axis of the blades can be readily ascertained when the device is operated, and injury to the perineum avoided.

The end portion of the indicator has an 15 oscillating handle adapted to swing about the axis of the indicator. The indicator is pivoted to an arm which can swing about the axis of a depending bar, thus giving universal movement to the handle. On the 20 shanks of one of the blades is mounted a swivel screw with clamping thumb nut whereby the jaws of the blades can be accurately set in their relation to each other or adjusted to move apart to suit the 25 conditions of the operation. The swivel screw has universal movement when the blades are adjusted to allow for the arc like swing of the shanks of the blades.

The novel features of the invention are 30 more fully described in the following specification and claims and illustrated in the accompanying drawing in which:—

Figure 1 represents a plan or top view of 35 an instrument embodying this invention. Fig. 2 is a side elevation thereof, the dotted lines in this figure showing the position of the instrument when operated. Fig. 3 is a vertical section taken along the line $x-x$ of Fig. 2. Fig. 4 is a vertical section taken 40 along line $y-y$ Fig. 3. Fig. 5 is a section taken along the line $z-z$ Fig. 2.

In this drawing the letter a designates a 45 pair of blades or jaws the sides of which are skeleton or open in form. These blades have the proper curvature in relation to the shanks to allow manipulation of the instrument, as is well understood by surgeons and others skilled in the art of operating the tool. These blades have shanks b forming a 50 continuation of the blades and the shanks are pivoted together at c . This pivot is fastened to one of the shanks and it is engaged by a slot formed in the other shank so that the two blades can be taken apart 55 when necessary to clean. One of the shanks has a downwardly formed extension d , and

the other shank has a depending bar e adjustably connected to the shank. By gripping the extension bar d and the depending bar e the blades can be actuated to adjust 60 the jaws of the blade. The depending bar e is adjustably connected to the shank by means of a headed stud f fastened to the bar and adapted to engage a key slot g in the bar. The bar e is equipped with a sliding 65 latch piece h which is attached to the bar by means of a thumb nut i . The upper portion of this latch co-operates with the stud f and when the thumb nut is fastened the latch will prevent movement of the bar. When 70 the thumb nut i is loosened the latch can be slid out of engagement with the headed stud f and the bar can be adjusted up or down on the depending shank of the blade. On the lower portion of the bar e is jointed an arm 75 j and to the free portion of this arm is pivoted an indicator k the stem of which carries a handle m . This handle can oscillate about the stem of the indicator and being pivoted to the jointed arm it can swing 80 about the axis of the depending arm, as stated, thus giving universal movement to the handle.

On the upper portion of each blade is mounted a post n and o respectively. 85 These posts have stems fitted into sockets in each of the blades and each post is prevented from being pulled out of the socket by a set screw p . The set screw engages an annular groove q located on the stem of each post, this construction allows each post to revolve on the blade. A screw r is pivoted at s to the post n while the stem of the screw is adapted to co-act with a slotted bifurcated portion of the post o . The screw r carries a nut t to engage the screw and co-operate with the post o to adjust and clamp the blades. In adjusting these blades by means of the screw the shanks of the blades will swing in an arc of a circle and in order to allow ready play or movement of the stem of the screw while in the slot the posts will swivel. In other words the blades can be adjusted while the screw stem is in the slot and then clamped in 90 their proper relative positions by adjusting the nut so that the jaws of the blade will grasp the object.

In operating the instrument the jaws are set a predetermined distance apart by adjusting the nut, the handle is grasped and the indicator pointed to gage the axis of the 100 105 110

blades as shown in dotted lines in Fig. 2 and by reason of the peculiar formation of the blades the head of the infant will be grasped by the jaws and drawn down the 5 superior strait to the pelvis and then drawn out without injury to the child or laceration of the perineum.

I claim:

- 10 1. A device of the character described, comprising a pair of gripping jaws pivotally connected together and provided with shank portions, one of said shank portions being bent to an angle from the general direction of the length of the jaw upon which 15 it is mounted, a stud and a pin carried by said last-mentioned shank portion, a rod provided with a key slot for receiving said stud and said pin, a latch slidably mounted upon said rod and provided with a surface 20 for engaging said stud, and means for hold-

ing said latch in fixed relation to said stud and said rod.

2. A device of the character described comprising a pair of jaws, a shank integral with one of said jaws and extending therefrom, a rod adjustably mounted upon said shank and adjustable in the general direction of the length thereof, an arm carried by said rod, a handle pivotally connected with said arm and an indicator for disclosing the position of said handle relatively to said arm. 25 30

In testimony whereof I have hereunto set my hand in the presence of two subscribing witnesses.

JOHN SKLAR.
